THREAD-CUTTING TEMPLE FOR LOOMS

George F. Bahan, Greenville, S. C.

Application November 24, 1950, Serial No. 197,327

8 Claims. (Cl. 139—303)

1

This invention relates to automatic filling replenishing looms and more especially to an improved thread-cutting temple therefor.

Heretofore, conventional thread-cutting temples have had a stationary blade, and the rear edge, which is that edge nearest the lay was disposed substantially flush with the rear surface of the temple and which had a pair of movable hook-shaped blades disposed adjacent one or both sides thereof, these blades being adapted to move rearwardly and downwardly simultaneously, in an arcuate path, upon a beat-up stroke of the lay of the loom on account of being engaged by the lay. The hook portions of the movable blades normally extend rearwardly beyond the rear face of the temple and the filling ends would be directed to the open lower edge thereof following a bobbin transfer operation.

However, as is well known to those familiar with the art, the filling ends are not placed under tension following a transfer operation and, as a result of the slack thereof, the filling ends quite often fall, by gravity, out of engagement with the hook at the rear end of the movable blades with the result that the filling may not be severed adjacent the selvage of the fabric being woven, often resulting in the loose ends being drawn back into the fabric being woven.

It is, therefore, an object of this invention to provide an improved thread-cutting temple which also has a stationary thread-cutting blade, the rear edge of which is disposed substantially flush with the enlarged rear edge of the temple and a pair of movable blades disposed adjacent opposed sides of the stationary blade, these movable blades being movable in a substantially straight line rather than arcuate so as to substantially reduce the wear inherent in the type of blade heretofore described. The improved blades are an integral part of a thread-cutting member and each has an upwardly and inwardly turned portion at the free end thereof defining a hook portion, this hook portion in each of the movable blades being overlapped by a rearwardly projecting portion of the blade disposed in substantially closely spaced relation to the upper edge of the portion of the blade which defines a hook thereon, whereby, upon a beat-up stroke of the lay, resulting in the movable blades being moved forwardly past the stationary blade, following a bobbin transfer operation, the filling ends ride up the outer surface of the projections forming said hook portions and are prevented from riding upwardly beyond a predetermined point by the overlapping projections on the blades. As the blades move forwardly, by virtue of a beat-up stroke of the lay, the yarn will be ensnared by the upwardly projecting hook portions thus insuring that the filling ends will be pulled by the hook portions past the stationary blades to be severed thereby although the filling ends may not be

2

under tension. It is evident that the upturned hook portions will prevent the filling ends from falling out of the hooks, by gravity, thus overcoming one of the major defects in the operation of thread-cutting temples which have heretofore been in use.

It is another object of this invention to provide an improved thread-cutting temple having an enlarged rear end portion provided with a forwardly and rearwardly extending slot therein and which slot is loosely penetrated by a forwardly and rearwardly movable thread-cutting member having spring means associated therewith which normally urges the same rearwardly or outwardly with respect to the enlarged portion of the temple. The thread-cutting member has a longitudinally extending slot therein which is loosely penetrated by a guide pin of substantially less diameter than the width of the slot and, upon a beat-up stroke of the lay, a downwardly projecting portion of the thread-cutting member is engaged by the lay and causes the blades thereon to move inwardly, and, as the blades move inwardly, the blades are so mounted in the temple that they will not engage the guide pin projecting therethrough during its movement nor will they engage the lower wall of the slot in which they are horizontally mounted, since the spring means will serve to hold the portion of the thread-cutting member remote from the blades thereof, which would be of substantially greater thickness than the blades thereof, upwardly against the upper wall of the slot in the enlarged portion of the temple thread-cutter. It is evident that a movable thread-cutting blade mounted in this manner would have a useful life surpassing by far the useful life of a blade mounted in the manner of the conventional blade as heretofore described.

Some of the objects of the invention having been stated, other objects will appear as the description proceeds when taken in connection with the accompanying drawings, in which—

Figure 1 is a top plan view of the improved thread-cutting temple disassociated from the loom;

Figure 2 is an enlarged isometric view of the movable thread-cutting member removed from the temple;

Figure 3 is an enlarged fragmentary rear end elevation of the improved thread-cutting temple and looking at the left-hand side of Figure 1;

Figure 4 is a fragmentary elevation looking at the left-hand side of Figure 3 and showing the blade portions of the improved thread-cutting member in a protruding position relative to the temple;

Figure 5 is a view partially in longitudinal vertical cross-section looking from a medial portion of the loom and toward the replenishing side, with parts broken away or omitted and showing the lay in a back-center position;

Figure 6 is a vertical sectional view taken substantially along the line 6—6 in Figure 3;

Figure 7 is a vertical sectional view taken substantially along the line 7—7 in Figure 3;

Figure 8 is an elevation looking substantially along the line 8—8 in Figure 7 and showing the movable thread-cutting member per se removed from the temple.

As the general operation and construction of an automatic filling replenishing loom and of a temple are well known and familiar to those skilled in the art, it is only necessary to illustrate and describe in detail those parts directly concerned with the present invention.

The loom comprises the usual frame having side frames 10, only one of which is shown, connected at the front by a breast beam 11. A supply of filled filling carriers or bobbins 12 is maintained in a hopper 13 mounted at the replenishing side of the loom. When the filling in the running shuttle 14 is substantially exhausted, suitable conventional detecting mechanism actuate the usual filling replenishment mechanism to force a fresh bobbin 12 into the shuttle 14 and discharge the exhausted bobbin from the shuttle.

The filling replenishing mechanism is conventional and is clearly shown in the patent to Stimpson No. 1,552,016 of September 1, 1925, and a further description thereof is thus deemed unnecessary. The shuttle 14 is adapted to be thrown across the race plate 16 of a lay 17 by conventional means not shown. The lay 17 is suitably secured to a pair of swords 20, only one of which is shown, and which are oscillated toward and from the breast beam by the usual pitman rods 21, pivotally connected, as at 22, to the swords 20. The swords 20 also support a reed cap 23 and a conventional reed 24 is supported between the reed cap 23 and the lay 17.

The temple, broadly designated at 25, comprises the usual stand 26 which is rigidly secured by a bracket 27 to the breast beam 11. In this stand 26 is mounted a temple arm 30 having an enlarged rear end portion 31 integral therewith which carries the usual temple head 32, this temple head 32 being secured to the rear end portion 31 of the temple arm 30 by any suitable means such as a screw 33 (Figure 7). The portion 32 also has a lateral extension 31a integral therewith. A spring, not shown, in the temple stand 26 acts normally to project the temple rearwardly towards the lay and on each beat-up stroke of the lay, a heel portion 34 depending from the temple arm 30 is struck by the lay and the temple is thus moved forwardly in the usual manner.

The temple head 32 is also held in proper relation to the enlarged rear portion 31 of the temple by means of a dovetail portion 36 which fits in a slot 37 in the enlarged rear portion 31 of the temple arm 30. It will be noted that the enlarged portion 31 of the temple arm 30 is joined to the temple arm 30 by a neck portion 40 which is disposed forwardly from and in spaced relation to the temple head 32.

The portion 31 of the temple arm 30 and the temple head 32 are provided with coinciding forwardly and rearwardly extending grooves therein which are indicated at 41 and 42, respectively, and which define the lower and upper walls, respectively, of a slot 43 in which the improved temple-cutting member, to be presently described, is adapted to operate. The proximate surfaces of the lateral extension 31a of the arm 30 and the temple head 32 are concave and have dis-

posed therebetween the usual temple roll 44 which is rotatably mounted on the reduced proximate end portions 45 and 46 of respective shoulder screws 50 and 51 which threadably penetrate the opposed downwardly projecting ends 32a and 32b, respectively, of the temple head 32.

The temple roll 44 has the usual spaced barbs 44a thereon which are used for the well known purpose of holding the fabric taut at the selvages thereof as the fabric is passed between the temple roll 44 and the concave upper surface of the lateral extension 31a of the temple arm 30.

The parts of the loom heretofore described, as well as the parts of the temple heretofore described, are conventional and it is with these parts that the present invention is adapted to be associated.

The rear face of the enlarged portion 31 of the temple arm 30 has a vertically extending slot 54 therein, the inner wall 55 of which is cut at an angle which extends downwardly and inwardly, as is clearly shown in Figures 6 and 7, and against which a dovetail portion 56 of a stationary thread-cutting blade 57 is secured by a screw 60, the head of which engages the rear surface of the dovetail portion 56 of the stationary blade 57 and which is threadably embedded in the enlarged portion 31 of the temple arm 30. This insures that the rear or cutting edge of the cutter blade 57 will extend in a vertical plane substantially flush with the rear surface of the enlarged portion 31 of the temple arm 30 and at right angles to the path of travel of a movable thread-cutting member designated broadly at 62.

This movable thread-cutting member 62 comprises a rearwardly extending portion 63 which is integral with a forwardly extending portion 64 disposed in vertical off-set relation to the portion 63 and from the front end of which an enlarged bunter portion 65 depends. The neck portion 40 of the temple arm 30 is vertically slotted, as at 66 (see Figure 1) in such a manner as to form a substantially vertical wall 67 and a horizontal upper wall 68 in the neck 40 of the temple arm 30 and to also form an angularly disposed wall 71 on the laterally extending portion 31a of the temple arm 30.

The neck portion 40 of the temple arm 30 has a shoulder 72 thereon (Figure 4) against which one end of a torsion spring 73 is urged, this torsion spring having several convolutions disposed around a pin 74 projecting from the temple arm 30 adjacent the shoulder 72. This torsion spring 73 extends downwardly and has several convolutions disposed around a pin 75 projecting from the enlarged bunter portion 65 of the thread-cutting member 62. This torsion spring 73 not only serves to normally urge the movable thread-cutting member 62 rearwardly so the blade portions thereof, to be presently described, will protrude from the rear surface of the enlarged portion 31 of the temple arm 30, but also serves to urge the thread-cutting member 62 upwardly to where the upper surface of the portion 64 will bear against the horizontal wall 68 of the slot 66. Since the portion 64 of the thread-cutting member 62 is stepped downwardly relative to the portion 63, shoulders 76 and 77 (Figures 6 and 7) are formed at the junction of the portions 64 and 63 of the thread-cutting member 62. Thus, the torsion spring 73 normally urges the shoulder 77 on the thread-cutting member 62 against the top edge of the wall 71 of the slot 66.

The rear portion 63 of the thread-cutting member 62 is provided with a longitudinally extend-

ing and vertically disposed slot 80 which extends from the rear edge thereof and terminates substantially midway of the portion 63. This slot defines a pair of spaced blade portions 81 and 82 (Figure 2) which straddle the stationary thread-cutting blade 57 heretofore described. The rear portion 63 of the thread-cutting member 62 also has a longitudinally and transversely extending slot 83 therein which is loosely penetrated by the pin 45, heretofore described, upon which one end of the temple roll 44 is rotatably mounted.

It will be noted in Figures 6 and 7 that the distance from the horizontal plane of the upper surface of the front portion 64 of the thread-cutting member 62 to the lower surface of the rear portion 63 is substantially less than the distance from the upper wall 68 of the slot 66 to the bottom of the groove 41 in the enlarged portion 31 and, thus, the torsion spring 73, in urging the upper surface of the portion 64 of the thread-cutting member 62 against the wall 68 of the slot 66 in the temple arm 30, causes the lower surfaces of the blades 81 and 82, on the portion 63 of the thread-cutting member 62, to normally remain out of engagement with the bottom of the groove 42 in the enlarged portion 31 of the temple arm 30.

Since the slot 83 is substantially larger than the pin 45 which loosely penetrates the same, it is thus seen that undue wear of the lower edges of the blade portions 81 and 82 of the thread-cutting member 62 is prevented. Also, the upper wall of the groove 42 in the temple head 32 is also spaced substantially above the upper edges of the blade portions 81 and 82 of the thread-cutting member 62 to prevent undue wear of the upper edges of the blade portions 81 and 82.

Now, referring to Figure 7, it is most clearly shown that the blade portions 81 and 82 of the thread-cutting member 62 are each provided with a transverse slot 85 which defines hook portions 86 as well as overlapping portions 87. The hook portions 86 curve upwardly and forwardly to thus guide the filling ends, upon a bobbin transfer operation, to the slot 85 to be ensnared by the hook portions 86 upon a beat-up stroke of the lay 17.

It is thus seen that, although there may be considerable slack in a filling end, since the hook portions 86 (Figures 6 and 7) slope upwardly and forwardly, the filling end will not only be directed into the slot 85 by the hook portions 86, but will also be supported thereby thus insuring that it will be held in engagement with the thread-cutting blades 81 and 82 upon the bunter 65 of the thread-cutting member 62 being engaged and moved from the position shown in Figures 1 and 7 to the position shown in Figure 6 by the lay 17 upon a beat-up stroke thereof following a bobbin transfer operation. The yarn will then be pulled by the hook portions 86 of the blades 81 and 82 past the stationary blade 57 to be severed thereby.

It will be observed in Figure 6 that, when the cutting member 62 is in a forward position as a result of the lay moving the same forwardly until it engages the heel 34 of the temple arm 30, the rear surface of the enlarged depending bunter portion 65 of the thread-cutting member 62 is disposed in the same horizontal plane as the rear surface of the heel 34 and the shoulder 76 is, at this time, spaced slightly rearwardly of the surface 67 on the neck portion 40 of the temple arm 30. However, due to the sudden impact of the lay against the bunter portion 65 of the thread-cutting member 62, it is likely that the

shoulder 76 will be thrown against the surface 67 of the neck 40 of the temple arm 30, the shoulder 76 thus serving to insure that the thread-cutting member 62 will not be thrown out of the temple arm 30.

Inasmuch as the upper surface of the front portion 64 of the thread-cutting member 62 has a greater area than the upper and lower edges of the blade portions 81 and 82 of the thread-cutting member 62, and also, due to the fact that the torsion spring 73 causes only the upper edge of the front portion 64 of the thread-cutting member 62 to move in sliding contact with any other part of the temple, such as against the surface 68, it is evident that the blade portions 81 and 82 of the thread-cutting member 62 will have a useful life far surpassing the period of usefulness which they would have in the event that either or both of their upper and lower edges were moved in sliding engagement with either the upper or lower surfaces of the slot 43. Of course, since the side walls of the slots within which the thread-cutting member 62 operates are spaced a substantially greater distance apart from each other than the horizontal thickness of the thread-cutting member 62, it is evident that wear of the side surfaces of the portions 63 and 64 of the thread-cutting member 62 would be negligible.

It is thus seen that I have provided an improved thread-cutting temple having a thread-cutting member 62 which may be easily and economically constructed and readily adapted to thread-cutting temples of the type heretofore in use. It is also evident that the improved thread-cutting member of the thread-cutting temple may operate continuously for a length of time far surpassing that of thread-cutting members heretofore in use and, further, I have provided means whereby the positive cutting of the filling ends is insured upon the filling ends being engaged by the blades of the improved thread-cutting member since it would be practically impossible for the filling ends to become separated from the blade portions of the thread-cutting member once they have been directed to the same.

In the drawings and specification there has been set forth a preferred embodiment of the invention and although specific terms are employed, they are used in a generic and descriptive sense only and not for purposes of limitation, the scope of the invention being defined in the claims.

I claim:

1. An improvement in thread-cutting temples for looms, said loom having a lay and also having an automatic filling replenishing mechanism and also having means securing the temple to the loom and said temple having a temple arm extending rearwardly therefrom provided with a heel portion adapted to be engaged by the lay upon a beat-up stroke thereof, said improvement comprising a thread-cutting member mounted for forward and rearward movement in a straight line in the temple arm, said thread-cutting member having at least one blade on the rear end thereof adjacent the lay, spring means normally urging the blade from a retracted position away from the lay to a projected position towards the lay, said blade having a transverse slot therein defining an upturned hook portion on the lower edge of the blade a fixed blade secured in the temple arm immediately adjacent the blade on the thread-cutting member and said hook portion being so positioned as to engage a filling end

upon the occurrence of a filling replenishing operation and to pull the filling end therewith upon being moved to retracted position by the lay.

2. An improvement in a thread-cutting temple for looms, said loom having a filling replenishing mechanism and also having an oscillatable lay adapted to engage the temple in the course of a beat-up stroke thereof, said improvement comprising said thread-cutting temple having a forwardly and rearwardly extending slot therein, a thread-cutting member mounted for horizontal forward and rearward movement in the slot in the temple, said thread-cutting member having at least one blade on the rear end thereof, spring means normally urging the blade to a projected position rearwardly of the temple, said spring means also serving to support the thread-cutting member so the blade on the thread-cutting member will not engage the walls of the slot in which it is mounted, said blade having a transverse slot in its rear end, the rear end of the transverse slot being partially closed by an upwardly projecting hook portion on the blade, means on the thread-cutting member engageable by the lay for moving the blade on the thread-cutting member to a retracted position upon a beat-up stroke of the lay and said hook portion being so positioned that, in the course of a beat-up stroke of the lay, the filling end resulting from a filling replenishing operation will be ensnared by the hook portion of said blade and drawn therewith into the temple as the blade is moved to retracted position to thus sever the filling end.

3. In a loom having a frame and a lay and a bobbin transfer mechanism and a temple disposed at the front of the lay, an improvement in said temple for severing filling ends which occur as a result of a bobbin transfer operation comprising a movable thread-cutting member mounted for movement in the temple in the direction of travel of the lay, tension means normally moving the thread-cutting member rearwardly in the temple, a thread-cutting blade on the rear end of the thread-cutting member and being provided with an upturned hook portion on the rear end thereof, a stationary cutter blade carried by the temple and disposed immediately adjacent the blade on the thread-cutting member and means engageable by the lay in the course of a beat-up stroke thereof for moving the thread-cutting member forwardly whereby the filling ends resulting from a bobbin transfer operation will be engaged and carried by the hook portion on the rear end of the movable thread-cutting blade past the stationary blade to be severed thereby upon a beat-up stroke of the lay.

4. In an automatic filling replenishing loom having a lay and also having a frame including a horizontal front frame member disposed forwardly of the lay, an element supported by said horizontal frame member and extending rearwardly therefrom and terminating at the beat-up point of the lay and adjacent the selvage of the fabric being woven and having a stationary thread-cutting element in the rear end thereof, an improved thread-cutting member adapted to cooperate with said stationary thread-cutting element for severing the filling ends resulting from a filling replenishing operation comprising a horizontally movable blade supported by said element secured to the frame and slidably engaging the stationary thread-cutting element at one side thereof, means normally causing said blade to protrude rearwardly of the stationary thread-cutting element at a point immediately above the

lay, an upwardly facing hook portion on the rear end of said movable blade and means responsive to a beat-up stroke of the lay for moving said movable blade forwardly past the stationary thread-cutting element whereby, in the course of a beat-up stroke, the filling ends resulting from a filling replenishing operation will be ensnared by said hook portion on the rear end of the movable cutting blade to be carried thereby past the stationary thread-cutting element to be severed thereby simultaneously with the completion of a beat-up stroke of said lay.

5. In an automatic filling replenishing loom having a lay and also having a frame including a horizontal front frame member disposed forwardly of the lay, an element supported by said horizontal frame member and extending rearwardly therefrom and terminating at the beat-up point of the lay and adjacent the selvage of the fabric being woven and having a stationary thread-cutting element in the rear end thereof, an improved thread-cutting member adapted to cooperate with said stationary thread-cutting element for severing the filling ends resulting from the filling replenishing operation comprising a horizontally movable blade supported by said element secured to the frame and slidably engaging the stationary thread-cutting element at one side thereof, means normally causing said blade to protrude rearwardly of the stationary thread-cutting element at a point immediately above the lay, and upwardly facing hook portion on the rear end of said movable blade, means responsive to a beat-up stroke of the lay for moving said movable blade forwardly past the stationary thread-cutting element whereby, in the course of a beat-up stroke, the filling ends resulting from a filling replenishing operation will be ensnared by said hook portion on the rear end of the movable cutting blade to be carried thereby past the stationary thread-cutting element to be severed thereby simultaneously with the completion of a beat-up stroke of said lay, and a protuberance on said movable blade disposed above and in the same vertical plane as the hook portion thereon to assist in directing said filling ends to the hook portion on the movable thread-cutting blade.

6. In an automatic filling replenishing loom having a lay and also having a frame including a horizontal front frame member disposed forwardly of the lay, an element supported by said horizontal frame member and extending rearwardly therefrom and terminating at the beat-up point of the lay and adjacent the selvage of the fabric being woven and having a stationary thread-cutting element in the rear end thereof, an improved thread-cutting member adapted to cooperate with said stationary thread-cutting element for severing the filling ends resulting from a filling replenishing operation comprising a horizontally movable blade supported by said element secured to the frame and slidably engaging the stationary thread-cutting element at one side thereof, means normally causing said blade to protrude rearwardly of the stationary thread-cutting element at a point immediately above the lay, an upwardly facing hook portion on the rear end of said movable blade, means responsive to a beat-up stroke of the lay for moving said movable blade forwardly past the stationary thread-cutting element whereby, in the course of a beat-up stroke, the filling ends resulting from a filling replenishing operation will be ensnared by said hook portion on the rear end of the movable cutting blade to be car-

ried thereby past the stationary theread-cutting element to be severed thereby simultaneously with the completion of a beat-up stroke of the lay, said element supported on the frame of the loom having a longitudinally extending slot therein in which said movable thread-cutting member is loosely mounted, said slot in the member supported on the frame of the loom being partially defined by an upper wall extending from a point forwardly of the blade on the movable thread-cutting member, the thread-cutting member having an upper surface disposed substantially forwardly of the thread-cutting blade carried thereby and spring means urging said upper surface of the thread-cutting member into engagement with said upper wall of the slot upon forward and rearward movement of the thread-cutting member, whereby said front upper portion of the thread-cutting member will move in sliding engagement with the upper wall of said slot thus obviating the necessity of the upper and lower surfaces of the blade of the thread-cutting member moving in sliding contact with any stationary part of the supporting means therefor.

7. In an automatic filling replenishing loom having a lay and also having a frame including a horizontal front frame member disposed forwardly of the lay, an element supported by said horizontal frame member and extending rearwardly therefrom and terminating at the beat-up point of the lay and adjacent the selvage of the fabric being woven and having a stationary thread-cutting element in the rear end thereof, an improved thread-cutting member adapted to cooperate with said stationary thread-cutting element for severing the filling ends resulting from the filling replenishing operation comprising a horizontally movable blade supported by said element secured to the frame and slidably engaging the stationary thread-cutting element at one side thereof, means normally causing said blade to protrude rearwardly of the stationary thread-cutting element at a point immediately above the lay, an upwardly facing hook portion on the rear end of said movable blade, means responsive to a beat-up stroke of the lay for moving said movable blade forwardly past the stationary thread-cutting element whereby, in the course of a beat-up stroke, the filling ends resulting from a filling replenishing operation will be ensnared by said hook portion on the rear end of the movable cutting blade to be carried thereby past the stationary thread-cutting element to be severed thereby simultaneously with the completion of a beat-up stroke of said lay, a protuberance on said movable blade disposed above and in the same vertical plane as the hook portion thereon to assist in directing said filling ends to the hook portion on the movable thread-cutting blade, said element supported on the frame of the loom having a longitudinally extending slot therein in which said movable thread-cutting member is loosely mounted, said slot in the member supported on the frame of the loom being partially defined by an upper wall extending from a point forwardly of the blade on the movable thread-cutting member, the thread-cutting member having an upper surface dis-

posed substantially forwardly of the thread-cutting blade carried thereby and spring means urging said upper surface of the thread-cutting member into engagement with said upper wall of the slot upon forward and rearward movement of the thread-cutting member, whereby said front upper portion of the thread-cutting member will move in sliding engagement with the upper wall of said slot thus obviating the necessity of the upper and lower surfaces of the blade of the thread-cutting member moving in sliding contact with any stationary part of the supporting means therefor.

8. In an automatic filling replenishing loom having a lay and also having a temple which extends above the lay in close proximity thereto upon a beat-up stroke of the lay and said temple having a stationary thread-cutting blade at the rear surface thereof, an improved thread-cutting member loosely mounted in the temple for forward and rearward movement therein, said thread-cutting member having a longitudinally extending slot therein defining a pair of closely spaced relatively thin vertically extending blade portions at the rear end of the thread-cutting member and which closely straddle said stationary thread-cutting blade, the blade portions having coinciding upwardly facing hook portions on the lower rear edges thereof and also having coinciding overlapping upper portions disposed in vertically spaced relation to the hook portions, spring means normally causing said hook portions on the blades to protrude rearwardly beyond the rear face of the stationary thread-cutting blade, said temple having a slot therein in which the thread-cutting member is mounted and the upper and lower walls of said slot adjacent the blade portions of the thread-cutting member being spaced from the corresponding upper and lower edges of the blade portions, said slot having a horizontal upper wall portion at the front end thereof, said spring means also serving to urge the upper surface of the front portion of the thread-cutting member against said front horizontal wall portion of the temple and means on the thread-cutting member engageable by the lay upon a beat-up stroke thereof to cause the filling ends resulting from a filling replenishing operation to be directed to and ensnared by the hook portions on the rear ends of the blades and to be pulled therewith past the stationary blade upon the completion of a beat-up stroke of the lay resulting in the filling ends being severed and whereby the relatively thin upper and lower edges of the blade portions of the thread-cutting member are prevented from engaging the upper and lower walls of the slot in which they are disposed.
